UNITED STATES PATENT OFFICE.

GREENLEAF WHITTIER PICKARD, OF AMESBURY, MASSACHUSETTS, ASSIGNEE TO
WIRELESS SPECIALTY APPARATUS COMPANY, OF BOSTON, MASSACHUSETTS, A
CORPORATION OF NEW YORK.

OSCILLATION-RECEIVING DEVICE.

1,136,047.

Specification of Letters Patent. Patented Apr. 20, 1915.

Original application filed July 24, 1911, Serial No. 640,106. Divided and this application filed December 8, 1913. Serial No. 805,240.

To all whom it may concern:

Be it known that I, GREENLEAF WHITTIER PICKARD, a citizen of the United States of America, and a resident of Amesbury, Massachusetts, have invented certain new and useful Improvements in Oscillation-Receiving Devices, the principles of which are set forth in the following specification and accompanying drawing, which disclose the 10 form of the invention which I now consider to be the best of the various forms in which the principles of the invention may be embodied.

This invention relates to wireless telegraphy detectors of the rectifier type, as now well known in the art, the object being to improve the electrical stability of the device; and is also a division of my application for patent Serial Number 640,106, filed 20 July 24th, 1911, and relates particularly to the arsenic member in contact with the silicon.

The invention consists in employing, in coöperation with the rectifying substance, another substance in contact therewith which possesses peculiar properties which result in very greatly improving the electrical stability of the device which includes the rectifying material.

30 Of the drawings, Figure 1 is a vertical section of an apparatus embodying the invention, and Fig. 2 is a vertical section taken transversely through A, B, Fig. 1.

Electrical instability has been a well known fault of the rectifier type of detector. That is, it has been found in practice that electrical currents or oscillations materially stronger than those of received signals, and such as "static" or "atmospheric," 35 and even received signals themselves when the sender is in close proximity to the detector, tend to reduce or even totally destroy the rectifying power of a detector in a given contact adjustment. This, of course, 40 is a serious thing in commercial telegraphy, because it requires a new contact adjustment, which it may not be possible to obtain until after a large part of the message has been lost. The present invention removes that 45 fault by producing a combination which remains in operative adjustment under substantially all conditions which have previously caused instability.

I have found that the invention is best executed by employing as the substance in contact with the rectifying material, a conductor which is characterized by considerable brittleness, such that at all times there is presented to the rectifying material a suitably small point of a rough or unpolished surface resulting from the fact that the brittle substance breaks off by use instead of becoming smooth or polished. Further than this present hypothesis, the reason is as yet obscure why, for a given adjustment, such class of materials makes the invention produce electrical stability, but it seems to be due to the fact that a suitably small contact can always exist. The fact is that all the materials which produce the desired result are characterized by extreme brittleness, and all of them I have found so far are included in a peculiar new class (brittle) of the materials classified by Mendeléeff in his well-known period-law table. (However, I do not wish to be understood as asserting that the brittleness necessarily has any essential relation to the operation.) Specifically the materials most useful within the invention, are the following conductors, *i. e.*, the metals arsenic (As), antimony (Sb), and bismuth (Bi), the best of which seems to be As. On reference to Mendeléeff's table, it will be seen that all these are comprised in group V, and in the odd-numbered series therein; *i. e.*, as is in the fifth series of group V, Sb is in the seventh series of group V, and Bi is in the eleventh series of group V. The materials under the even-numbered series seem not so well adapted for use in the invention, although of course, I desire to include in the claims, all materials which are so adapted in greater or less degree. However, the materials which now seem most useful under the invention, are included in said special class of Mendeléeff's group V and all characterized by extreme brittleness, as well as by other properties, among which are that there normally exists a tarnish or oxid coat on any exposed surface of these materials; and in use under the invention it is this tarnished surface which is used in contact with the rectifying material, that is to say, the surface becomes tarnished so quickly that notwithstanding the readiness of fracture, the fracture sur-

face becomes tarnished almost immediately, and I do not assert that the tarnish has anything to do with the action of the device. The rectifying material which up to the 5 present time I have found to be most usefully employed in combination with these brittle conductors, is the element silicon, and particularly when used with a substantially rough or unpolished surface, such as 10 an ordinary fracture face, in contact with the brittle conductor such as arsenic, etc.

The drawings show a detector-holder of substantially the construction shown in my prior Patent 912,726, dated February 16th, 15 1909. The rectifying material S, such as silicon, and the coöperating conductor A, such as arsenic, are held, preferably by soft readily fusible metal, in cups, one or both of the 20 cups being adjustable so that contact selection may be had between S and A. As shown, the silicon preferably has a rough 25 surface presented to A. Likewise, the surface of the brittle conductor A which is presented to S, is rough, produced as by making a fracture.

So far as I have determined as yet, the coöperating contact members of this invention do not of themselves have the characteristic 30 of rectifying, except as to such extent as may be due to the tarnish on their surface. Hence their function is substantially limited to that of furnishing a stable contact for the other or rectifying member; although it would not be a departure from the invention to employ 35 a material which also rectified in addition to executing the functions of the coöperating contact members of the invention.

Of course the invention may be embodied 40 in various mechanical forms, and by way of illustration, reference is here made to an-

other desirable form, which consists in employing one of the brittle conductors, such as arsenic, as the sleeve 7 (or as a lower part of such sleeve) of Fig. 1 of my prior Patent 836,531, dated November 20th, 1906. Preferably a small mass of the arsenic is soldered or welded to the lower end of the sleeve 7, and the contact surface of the arsenic roughened as by making a fracture face. 45

The invention is not of course, limited to the elements arsenic, etc., but includes all materials which possess the properties of the same which are useful in the invention; and such materials may include conducting chemical compounds or alloys which possess 55 such properties although the constituents thereof might lack such properties.

The expression "rough surface" in the claims, implies, as stated above, that the operative portion is probably a single point effectively projecting from such surface. 60

1 claim:—

1. As a receiving device for wireless telegraphy oscillations, the combination with a member containing silicon, of a contacting 65 member containing the metal arsenic.

2. As a receiving device for wireless telegraphy oscillations, the combination with a member consisting of the element silicon, of a contacting member consisting of the metal 70 arsenic.

3. As a receiving device for wireless telegraphy oscillations, the combination with a silicon member, of an arsenic member having a rough surface in contact with said silicon member. 75

GREENLEAF WHITTIER PICKARD.
